CLAIM

The ornamental design for a set of dishware, as shown and described.

DESCRIPTION

FIG. 1 is an exploded top perspective view of a set of dishware of nine different component types, namely, (1) a topmost component of a single band; (2) a first component type below the topmost component of a single overall lid; (3) a second component type below the topmost component of two identical smaller lids, wherein there are two such second component types; (4) a third component type below the topmost component of two identical quarter containers, wherein there are two such third component types; (5) a fourth component type below the topmost component of a half container; (6) a fifth component type below the topmost component of a tray; (7) a sixth component type below the topmost component of a tray skirt; (8) an seventh component type below the topmost component of a bowl; and (9) an eighth component type below the topmost component of a bowl bottom cover;

FIG. 2 is a perspective view of the set of dishware from FIG. 1 but shown in a stacked configuration;

FIG. 3 is a front view or a rear view of the set of dishware from FIG. 1 but shown in the stacked configuration of FIG. 2;

FIG. 4 is a side view (left or right) of the set of dishware from FIG. 1 but shown in the stacked configuration of FIG. 2;

FIG. 5 is a top view of the set of dishware from FIG. 1 but shown in the stacked configuration of FIG. 2;

FIG. 6 is a bottom view of the set of dishware from FIG. 1 but shown in the stacked configuration of FIG. 2;

FIG. 7 is a front view or a rear view of the topmost component from FIG. 1;

FIG. 8 is a side view (left or right) of the topmost component from FIG. 1;

FIG. 9 is a top view of the topmost component from FIG. 1;

FIG. 10 is a bottom view of the topmost component from FIG. 1;

FIG. 11 is a front view or a rear view of the first component type below the topmost component from FIG. 1;

FIG. 12 is a side view (left or right) of the first component type below the topmost component from FIG. 1;

FIG. 13 is a top view of the first component type below the topmost component from FIG. 1;

FIG. 14 is a bottom view of the first component type below the topmost component from FIG. 1;

FIG. 15 is a bottom perspective view of the first component type below the topmost component from FIG. 1;

FIG. 16 is a front view of the second component type below the topmost component from FIG. 1;

FIG. 17 is a rear (back) view of the second component type below the topmost component from FIG. 1;

FIG. 18 is a left side view of the second component type below the topmost component from FIG. 1;

FIG. 19 is a right-side view of the second component type below the topmost component from FIG. 1;

FIG. 20 is a top view of the second component type below the topmost component from FIG. 1;

FIG. 21 is a bottom view of the second component type below the topmost component from FIG. 1;

FIG. 22 is a bottom perspective view of the second component type below the topmost component from FIG. 1;

FIG. 23 is a front view of the third component type below the topmost component from FIG. 1;

FIG. 24 is a rear (back) view of the third component type below the topmost component from FIG. 1;

FIG. 25 is a left-side view of the third component type below the topmost component from FIG. 1;

FIG. 26 is a right-side view of the third component type below the topmost component from FIG. 1;

FIG. 27 is a top view of the third component type below the topmost component from FIG. 1;

FIG. 28 is a bottom view of the third component type below the topmost component from FIG. 1;

FIG. 29 is a front view of the fourth component type below the topmost component from FIG. 1;

FIG. 30 is a rear (back) view of the fourth component type below the topmost component from FIG. 1;

FIG. 31 is a side view (left or right) of the fourth component type below the topmost component from FIG. 1;

FIG. 32 is a top view of the fourth component type below the topmost component from FIG. 1;

FIG. 33 is a bottom view of the fourth component type below the topmost component from FIG. 1;

FIG. 34 is a front view, a rear view, or a side view of the fifth component type below the topmost component from FIG. 1;

FIG. 35 is a top view of the fifth component type below the topmost component from FIG. 1;

FIG. 36 is a bottom view of the fifth component type below the topmost component from FIG. 1;

FIG. 37 is a front view, a rear view, or a side view of the sixth component type below the topmost component from FIG. 1;

FIG. 38 is a top view of the sixth component type below the topmost component from FIG. 1;

FIG. 39 is a bottom view of the sixth component type below the topmost component from FIG. 1;

FIG. 40 is a front view, a rear view, or a side view of the seventh component type below the topmost component from FIG. 1;

FIG. 41 is a top view of the seventh component type below the topmost component from FIG. 1;

FIG. 42 is a bottom view of the seventh component type below the topmost component from FIG. 1;

FIG. 43 is a front view, a rear view, or a side view of the eighth component type below the topmost component from FIG. 1;

FIG. 44 is a top view of the eighth component type below the topmost component from FIG. 1; and,

FIG. 45 is a bottom view of the eighth component type below the topmost component from FIG. 1.
